UNITED STATES PATENT OFFICE

2,632,560

CONVEYER ROLL ASSEMBLY

Fred J. Wright, Columbus, Ohio, assignor to The Jeffrey Manufacturing Company, a corporation of Ohio

Application June 6, 1950, Serial No. 166,340

16 Claims. (Cl. 198—192)

1

This invention relates to a resilient conveyer roll that may be used with advantage to support resiliently a conveyer belt, particularly at that portion or position along its length where materials are loaded or spilled upon it.

One object of the invention is to provide an improved conveyer roll assembly wherein the roll element includes a plurality of side by side disc elements provided with rims supported through resilient means, such, for example, as discs of rubber or the like, each disc element including a portion having substantially equal circumferential cross sectional areas at each of a plurality of circular cross sections taken therethrough substantially concentric with the rim or the axis of rotation of the roll element.

Another object of the invention is to provide an improved conveyer roll assembly wherein the roll element is resilient in itself and is carried by bearings that are resiliently supported, thereby to protect the bearings from shocks resulting from large pieces of material falling upon the conveyer belt or passing over the roll upon the conveyer belt.

Another object of the invention is to provide an improved conveyer roll assembly including one or more roll elements or a roll element, per se, that includes a central portion of resilient material, such, for example, as rubber or the like, that has substantially equal circumferential cross sectional areas at each of a plurality of circular sections taken therethrough concentric with the axis of rotation of the element and which central portion is substantially surrounded by a non-deformable means whereby the roll element possesses substantially uniform elastic characteristics particularly to radial distortion.

Other objects of the invention will appear hereinafter, the novel features and combinations being set forth in the appended claims.

In the accompanying drawings:

Fig. 1 is a view of a conveyer troughing roll assembly embodying the features of the invention, the view being partly in section and partly in elevation;

Fig. 2 is an end view in elevation on a smaller scale of the conveyer troughing roll assembly seen in Fig. 1; and

Fig. 3 is a side view in elevation on a smaller scale of one of the roll elements of the conveyer troughing roll assembly seen in Fig. 1.

In the drawings there is shown a conveyer troughing idler roll assembly 10 that includes a main frame or chair 11, a plurality of bearing receiving and supporting housings 12 and 13,

and three identical idler roll element assemblies or units 14, 15 and 16 that are carried through the housings 12 and 13 upon the main frame or chair 11.

5 Main frame or chair 11 includes a base member 17 of inverted V-shaped cross section, the outer end portions 18 of which are bent to extend outwardly and upwardly from the central portion 19 to provide a symmetrical base. Extending upwardly, one from each of the outer ends of the central portion 19 of the base member 17, chair 11 includes two brackets or legs 20 and at each of the outermost ends of the sections 18 it includes a bracket or leg 21 that extends upwardly and inwardly. Brackets and legs 20 and 21 are identical and each is welded at its bottom to the base member 17. The top of each bracket or leg 20 and 21 is slotted vertically to provide a yoke 22 (see Fig. 2) that receives one of the housings 12 or 13.

10 Housings 12 and 13 are castings provided with U-shaped grooves or channels 23 in their outside surfaces that interfit slidably with the yokes 22 of brackets or legs 20 or 21 and they are shaped to cooperate with the yokes 22 to prevent lateral shifting and rotation of the housings 12 and 13 with respect to the brackets or legs 20 and 21 that support them.

15 Each outer bearing housing 13 forms a cup-shaped chamber 24 at the outside of a machined cylindrical portion 25 that receives a resilient or cushion bearing support 26 including a ring 27 of grease and oil resistant synthetic rubber or like material vulcanized between an outer ring or rim 28 that fits tightly within the cylindrical portion 25 of housing 13, and an inner ring 29 that is ground spherically internally to receive the spherically ground outer race of an anti-friction bearing 30. Ring 29 and the outer bearing race cooperate to provide self-aligning mounting features for the bearing 30. Chamber 24 cooperates with the resilient or cushion bearing support 26 and the bearing 30 to form a reservoir for lubricant for the bearing.

20 Each of the center bearing housings 12 includes two spaced machined cylindrical portions 31 and 32, the axes of which intersect and are parallel to the portions 18 and 19, respectively, of main frame or chair 11, and each of these cylindrical portions 31 and 32 receives a resilient or cushion bearing support 26 for one of the anti-friction bearings 30 that support adjacent ends of roll assemblies 14 and 15 or 15 and 16. The cylindrical portions 31 and 32 of housing 12 are spaced-apart laterally to provide an area 33 between

them that functions when the resilient or cushion bearing supports 26 and bearings 30 are mounted in the cylindrical portions 31 and 32 to form a chamber or compartment for lubricant for the bearings.

Each idler roll assembly or unit 14, 15 and 16 includes a pair of identical metal end disc members 34 provided with peripheral tires 35 of rubber or material having like resilient characteristics. The outside of each disc member 34 is recessed centrally to provide a well having a tapered cylindrical outer wall 36 that fits over a collar of one of the cylindrical portions 25, 31 or 32 of a housing 12 or 13.

Centrally or upon its axis of rotation disc member 34 is bored axially and at its outside and at the center of the recessed or well portion thereof there is a laterally extending integral collar, boss or hollow stub shaft 37 that extends into the inner race of one of the bearings 30 and is supported thereby. Opposite the boss 37 the disc 34 includes a second laterally extending integral collar, boss or hollow stub 38 that receives a center or tubular hub member 39 that functions to space the opposite end discs 34 and to carry a plurality of resilient idler roll elements, discs or wheels 40 placed thereon in side by side relation. A rod 41 provided with nuts upon its opposite ends extends axially through the end discs 34 and central or tubular member 39 and clamps the elements of the resilient idler roll assembly or unit together.

Roll assemblies or units 14, 15 and 16 of idler roll assembly 10 carry and trough the working run of the belt, indicated in dot-dash lines in Fig. 1 of the drawings, of an endless belt conveyer and in practice a plurality of idler roll assemblies 10 are positioned to carry that portion of the working run of the conveyer where material is loaded or spilled upon it. It may be mentioned that the working run of the conveyer belt is normally troughed to such shape that its under side does not normally ride upon the tires 35 of the adjacent end discs 34 of roll assemblies 14 and 15, and 15 and 16 and that the end discs 34 are provided with the resilient tires 35 only to arrest and prevent excessive distortion of the conveyer belt thereabove as a result of overloading of it or extremely heavy impacts upon it resulting from large pieces of material striking directly that area of the belt directly above the tires 35.

Each of the resilient idler roll elements, discs or wheels 40 includes a center mounting or hub sleeve 42 that fits tightly upon the center or tubular hub member 39, and surrounding and preferably vulcanized to the sleeve 42 is a disc or central portion 43 made of resilient material, such, for example, as rubber or material having like resilient characteristics. Upon its peripheral surface, disc or central portion 43 has mounted upon it a rim, ring or tire 44 that is substantially non-deformable. As indicated in Fig. 1 of the drawings, rim, ring or tire 44 is T-shaped in cross section with the leg of the T imbedded in the resilient disc or central portion 43. Rim or ring 44 and the central rim mounting resilient disc 43 are preferably vulcanized together.

The disc or central portion 43 of each roll element 40 is so shaped cross sectionally, as seen in Fig. 1 of the drawings, that it includes a portion having substantially equal circumferential cross sectional areas at any of successive cross sections taken therethrough circularly or concentrically with the rim, ring or tire 44 or the axis of rotation of the portion 43. This portion of substantially equal circumferential cross sectional

areas is defined generally by the radially innermost edges of the laterally flared or rim portion of resilient disc 43 adjacent the center leg of the T-shaped rim, ring or tire 44 and the outside circumferential surface of the center mounting sleeve 42 to which the resilient disc or rim mounting member 43 is vulcanized.

In Figs. 1 and 3 of the drawings there is indicated by the dot-dash lines A, B and C three of such circumferential cross sections above referred to and the equal circumferential areas mentioned are determined by calculating the circumferential areas of the disc 43 of resilient material where it is cut by the section lines A, B and C, that is, the circumferential area of disc 43 at section A substantially equals the circumferential areas of disc 43 at sections B and C.

It is important to note that by the construction herein disclosed, the resilient roll elements, discs or wheels 40 include a mounting means for a substantially non-deformable ring, rim or tire that possesses substantially uniform elastic characteristics particularly to radial distortion produced therein when the rim, ring or tire is displaced axially or radially with respect to the mounting means for the central disc 43 of resilient material.

In known constructions of resilient conveyer discs the material at the periphery thereof and adjacent the point of impact or load may tend to dent or flatten adjacent said point of contact or certain circumferential cross sectional areas of the disc may be required to support more load per square inch of area than others. With the construction disclosed herein the load supported upon the periphery of the disc or wheel 40 tends to displace the entire peripheral surface including the substantially non-deformable tire 44 with respect to the axis of rotation of the disc or wheel 40, and the load that is tending to displace the outer peripheral surface or rim of the disc 43 is distributed substantially equally throughout that portion of it where the successive circumferential cross sectional areas are equal.

Each of the rolls 14, 15 and 16 includes three of the disc or wheel elements 40, and in considering the rolls 14, 15 and 16 it is to be noted that each of them includes a hub portion comprised of the central portions of the spaced end discs, the center or tubular hub member 39 and the tubular hub sleeves 42 of the resilient roll elements, discs or wheels 40 and they each include three rim portions each of which is carried by a disc portion of resilient material between the rim portion and hub portion of the roll. Each of the rim portions of the wheels 40 may be considered as being the radially outermost portion of it that is flared laterally to accommodate the tire 44. Each of the disc portions of resilient material increases in its axial dimension or thickness from this outer radial rim portion of the wheel 40 to the inner radial rim portion thereof which is adjacent the tubular hub sleeve 42 of the hub portion of the idler and this increase in the axial dimension of the resilient disc is such that successive circumferential cross sectional areas of the disc between the radially outermost rim portion and the hub portion are substantially equal. Because of the increase in the axial dimension of the disc of resilient material so that successive circumferential cross sectional areas of it are substantially equal any load supported upon the rim portion of each of the discs or wheels 40 will be distributed equally throughout the resilient disc, that is, the load carried per square inch of area at any of the circumferential cross sectional areas will be sub-

stantially equal because the areas of each of the circumferential cross sectional areas are substantially equal.

It is also important to note that because the bearings 30 are supported through resilient rings or cushions 26 and because the idler roll assemblies or units 14, 15 and 16 are resilient in themselves, the bearings 30 are cushioned against shock resulting from large pieces of material falling upon the conveyer or riding over the roll units 40 thereon, thereby substantially eliminating Brinelling effect upon the bearing parts.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A conveyer troughing roll assembly including three roll elements arranged to support and trough a conveyer element travelling thereover, chair means for supporting said roll elements as aforesaid including spaced upstanding brackets slotted vertically at their tops, a bearing receiving housing carried by each of said upstanding brackets, said housings including channel means slidably into said bracket slots, self-aligning anti-friction bearing means in said housings, cushion means supporting said bearings in said housings, said roll elements including bearing receiving means at each of their ends supported by said bearings in adjacent of said housings, each of said roll elements including spaced end discs, resilient tires on said end discs, a plurality of side by side disc members between said spaced end discs each including a substantially non-deformable rim means, and a resilient mounting member for said substantially non-deformable rim means, said mounting member including a portion having substantially equal circumferential cross sectional areas at each of a plurality of circular sections taken therethrough substantially concentric with said substantially non-deformable rim, said resilient tires on adjacent of said end discs normally being out of engagement with said conveyer element and functioning to prevent excessive distortion of said conveyer element thereabove as a result of heavy impacts upon it.

2. A conveyer troughing roll assembly including roll elements arranged to support and trough a conveyer element travelling thereover, chair means for supporting said roll elements as aforesaid including spaced upstanding brackets, a bearing receiving housing carried by each of said upstanding brackets, anti-friction bearing means in each of said housings, cushion means supporting said bearings in said housings, said roll elements including bearing receiving means at each of their ends supported by said bearings in adjacent of said housings, each of said roll elements including spaced end discs, resilient tires on said end discs, a plurality of side by side disc members between said spaced end discs each including a substantially non-deformable rim means, and a resilient mounting member for said substantially non-deformable rim means, said mounting member including a portion having substantially equal circumferential cross sectional areas at each of a plurality of circular sections taken therethrough substantially concentric with said substantially non-deformable rim, said resilient tires on adjacent of said end discs normally being out of engagement with said conveyer element and functioning to prevent excessive distortion of said conveyer element thereabove as a result of heavy impacts upon it.

engagement with said conveyer element and functioning to prevent excessive distortion of said conveyer element thereabove as a result of heavy impacts upon it.

3. A conveyer troughing roll assembly including roll elements arranged to support and trough a conveyer element travelling thereover, chair means for supporting said roll elements as aforesaid including spaced upstanding brackets, a bearing receiving housing carried by each of said upstanding brackets, anti-friction bearing means in each of said housings, cushion means supporting said bearings in said housings, said roll elements including bearing receiving means at each of their ends supported by said bearings in adjacent of said housings, each of said roll elements including spaced end discs, resilient tires on said end discs, a plurality of side by side disc members between said spaced end discs each including a substantially non-deformable rim means, and a resilient mounting member for said rim means, said resilient tires on adjacent of said end discs normally being out of engagement with said conveyer element and functioning to prevent excessive distortion of said conveyer element thereabove as a result of heavy impacts upon it.

4. A conveyer troughing roll assembly including roll elements arranged to support and trough a conveyer element travelling thereover, chair means for supporting said roll elements as aforesaid, spaced cushion means carried by said chair means, bearing means supported by said cushion means, said roll elements including bearing receiving means at each of their ends supported by said bearings in adjacent of said cushion means, and each of said roll elements including spaced end discs, resilient tires on said end discs, a plurality of side by side disc members between said spaced end discs each including a substantially non-deformable rim means, and a resilient mounting member including a portion having substantially equal circumferential cross sectional areas at each of a plurality of circular sections taken therethrough substantially concentric with said substantially non-deformable rim, said resilient tires on adjacent of said end discs normally being out of engagement with said conveyer element and functioning to prevent excessive distortion of said conveyer element thereabove as a result of heavy impacts upon it.

5. A conveyer troughing roll assembly including roll elements arranged to support and trough a conveyer element travelling thereover, chair means for supporting said roll elements as aforesaid, spaced cushion means carried by said chair means, bearing means supported by said cushion means, said roll elements including bearing receiving means at each of their ends supported by said bearings in adjacent of said cushion means, and each of said roll elements including spaced end discs, resilient tires on said end discs, a plurality of side by side disc members between said spaced end discs each including a substantially non-deformable rim means, and a resilient mounting member for said rim means, said resilient tires on adjacent of said end discs normally being out of engagement with said conveyer element and functioning to prevent excessive distortion of said conveyer element thereabove as a result of heavy impacts upon it.

6. A conveyer roll assembly including a chair means for supporting a roll element, spaced cushion means carried by said chair means, bearing means supported by said cushion means, bearing receiving means on the ends of said roll

element, said roll element being supported between said bearing means and including spaced end discs, resilient tires on said end discs, a plurality of side by side disc members between said spaced end discs, each including a substantially non-deformable rim means, and a resilient mounting member for said substantially non-deformable rim means, said mounting member including a portion having substantially equal circumferential cross sectional areas at each of a plurality of circular sections taken therethrough substantially concentric with said substantially non-deformable rim.

7. A conveyer roll assembly including a chair means for supporting a roll element, spaced cushion means carried by said chair means, bearing means supported by said cushion means, bearing receiving means on the ends of said roll element, said roll element being supported between said bearing means and including spaced end discs, resilient tires on said end discs, a plurality of side by side disc members between said spaced end discs, each including a rim means, and a resilient mounting member for said rim means.

8. A conveyer roll assembly including a chair means for supporting a roll element, spaced cushion means carried by said chair means, bearing means supported by said cushion means, bearing receiving means on the ends of said roll element, said roll element being supported between said bearing means and including a plurality of side by side disc members each including a substantially non-deformable rim means, and a resilient mounting member for said substantially non-deformable rim means, said mounting member including a portion having substantially equal circumferential cross section, areas at each of a plurality of circular sections taken therethrough substantially concentric with said substantially non-deformable rim.

9. A conveyer roll assembly including a chair means for supporting a roll element, spaced cushion means carried by said chair means, bearing means supported by said cushion means, bearing receiving means on the ends of said roll element, said roll element being supported between said bearing means and including a plurality of side by side disc members each including a substantially non-deformable rim means, and a resilient mounting member for said substantially non-deformable rim means.

10. A conveyer roll including a plurality of side by side members each including a rim means and a resilient mounting member for said rim means, said mounting member including a portion having substantially equal circumferential cross sectional areas at each of a plurality of circular sections taken therethrough substantially concentric with said rim, bearing means supporting said roll, and cushion means supporting said bearing means.

11. A conveyer roll including a plurality of side by side members each including a rim means, and a resilient mounting member for said rim means, said mounting member including a portion having substantially equal circumferential cross sectional areas at each of a plurality of

circular sections taken therethrough substantially concentric with said rim.

12. A conveyer roll member including a rim means, and a resilient mounting means for said rim means, said mounting means including a portion having substantially equal circumferential cross sectional area at each of a plurality of sections taken substantially concentric with said rim means.

13. A conveyer roll including concentric circular rim and hub members, and a disc of resilient material interposed between each said rim and hub members, said disc including a portion having substantially equal circumferential cross

15 sectional areas at each of a plurality of concentric circular sections taken therethrough whereby said disc possesses substantially uniform elastic characteristics to radial distortion produced therein when said rim and hub members are displaced radially relative to each other.

14. A conveyer roll assembly including spaced end discs, resilient tires on said end discs, a plurality of side by side disc members between said spaced end discs each including a rim means and

25 a resilient mounting member for said rim means, said mounting member including a portion having substantially equal circumferential cross sectional areas at each of a plurality of circular sections taken therethrough substantially concentric with said rim, anti-friction bearing means supporting said roll, and cushion means supporting said anti-friction bearings means.

15. A conveyer roll element including a central portion formed of resilient material having substantially equal circumferential cross sectional areas at each of a plurality of circular sections taken therethrough concentric with the axis of rotation thereof, and a substantially non-deformable rim means surrounding said area 35 whereby said roll element possesses substantially uniform elastic characteristics to radial distortion.

16. An idler roll including a hub portion, a rim portion and a disc portion between said hub and rim portions, said rim portion including a substantially non-deformable tire, said disc portion being of resilient material and increasing in its axial dimension from the outer radial portion thereof adjacent said rim portion to the inner radial portion thereof adjacent said hub, said increasing axial dimension being such that successive circumferential cross sectional areas of said disc between said hub and said rim are substantially equal.
